United States Patent Office

Des. 195,102
Patented Apr. 23, 1963

195,102

BOTTLE

Ernest L. Du Pree, New York, N.Y., assignor to Schenley Industries, Inc., New York, N.Y., a corporation of Delaware

Filed Mar. 21, 1962, Ser. No. 69,360

Term of patent 14 years

(Cl. D58—6)

Fig. 1

Fig. 2

The rear face and the opposite side of the bottle correspond respectively with FIGURES 1 and 2.

I claim:

The ornamental design for a bottle, as shown and described.
